ARTHUR W. CLAUDE, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

ELECTRIC-LAMP SOCKET.

1,082,404.

Specification of Letters Patent. Patented Dec. 23, 1913.

Application filed May 6, 1912. Serial No. 695,352.

To all whom it may concern:

Be it known that I, ARTHUR W. CLAUDE, a citizen of the United States of America, residing in the city of Bridgeport, in the county of Fairfield and State of Connecticut, have invented certain new and useful Improvements in Electric-Lamp Sockets, of which the following is a specification.

My invention relates to key sockets for electric incandescent lamps, in which a rotating key is used to effect both a quick make and a quick break of the circuit, and the main object of my invention is to provide a simple construction of mechanism by which such operation can be effected with a positive action by turning the key in either direction.

In the accompanying drawings, Figure 1 is a vertical section through a socket embodying my invention; Fig. 2 is a transverse section at right angles to the view, Fig. 1, the shell and cap being omitted; Fig. 3 is a perspective view of several parts of the key mechanism detached from each other; Fig. 4 is a perspective view of the latch plate looked at from the opposite side from which it is seen in Fig. 3; Fig. 5 is a perspective view of the rotary switch piece; Fig. 6 is a transverse section through the key spindle and showing the cam.

The socket is provided with any suitable form of insulating body carrying the wire terminals and lamp terminals, all adapted to be inclosed within the usual lined metal shell S and cap C.

In the construction shown, the insulating body consists of two juxtaposed chambered blocks D, D¹ of porcelain or other insulating material mechanically united together by metal standards 12 and 13, which at the same time constitute the wire terminals, being provided with binding screws 14, 15, Fig. 2.

Upon the lower face of the lower block D are the lamp-receiving terminals 16 and 17, shown as of the Edison type, namely, one a central spring and the other a screw-threaded shell. The metal terminal 13 is in electrical communication with the screw shell 17, while the central spring contact 16 is in electrical communication with a spring contact 18 in the bottom of the central switch chamber formed by recesses in the juxtaposed faces of the insulating blocks D, D¹.

The key-spindle 20, provided with the

usual handle 19, is mounted to turn in bearings in a frame 21, which may be secured in the switch chamber by a screw 22, Fig. 1, inserted from the underside of the lower insulating block D. A rotary switch piece 26, in the shape of an open rectangular frame, shown separately in Fig. 5, is mounted upon this spindle 20 so as to be free to turn independently thereof. This switch piece, when in the vertical position shown in Figs. 1 and 2, bears at its lower side against the contact 18, and at its upper side against a spring contact 27 connected with the terminal 12, Fig. 2, so that then the circuit will be from this terminal 12, contact 27, switch piece 26, and contacts 18 and 16, to the lamp, then to the screw shell 17, and terminal 13. By turning the switch piece away from this position, the circuit will be broken at the two points 18 and 27.

The spindle 20 has affixed to it a cam 23 in the form of a circular disk with a cam slot 24 cut through it, one end x of the cam slot being close to the spindle, and the other end y at a distance therefrom, as best shown in Figs. 5 and 6. Into this slot projects a pin 25 carried by a latch plate 36 (Fig. 3) which is slotted at 28 for the passage of the spindle 20, and has at its opposite edges guide flanges 29 embracing the edges of the cam disk 23, so that when the latter is turned in one direction or the other, the latch plate 36 can slide transversely with relation to the shaft under the action of the cam upon the pin 25. The back of the latch plate 36 carries a latch 30, adapted to engage stops upon the adjacent end plate of the frame 21. These stops are in two sets of four each, one set 31 being adapted to coöperate with the latch 30 when the key is turned in one direction (clockwise in Fig. 3), while the other set 32 coöperate with the latch 30 when the key is turned in the other direction. These stops are in such positions as to lock the rotary switch piece, either in the vertical "on" position, such as seen in Figs. 1 and 2, or in the horizontal "off" position, the rotary switch piece moving a quarter turn in changing from one position to the other, and the latch 30 being normally held between two adjacent stops 31 and 32.

Around the spindle 20, within the switch piece, is coiled a spring 33, whose crossed ends embrace an arm of the switch piece 26 and a pin 34 on the cam disk. The pin 25 on

the latch plate 36 projects sufficiently far through the slot of the cam disk 23 to enter a slot 35, (Figs. 1 and 5) of the rotary switch piece 26, so that the latter can turn 5 on the shaft only with the latch plate 36.

Assuming the parts to be in the positions shown in Figs. 1 and 2, and the spindle 20 to be turned clockwise, Figs. 2, 3 and 6, the pin 25 on the latch plate 36 will be drawn 10 toward the spindle 20, by the end *x* of the cam slot, until the latch 30 is drawn radially inward clear of the inner edge of the bottom lock 31, which detains it. Meantime the spring 33 will have been tensioned by the 15 movement of the pin 34 with the cam disk 23, so that when the latch 30 has been freed from the stop 31, the switch piece will be thrown forward clock-wise, to make a quick break of the circuit. The latch will be 20 thrown radially outward again at once by this forward movement, to enter between and come into locking engagement with the next pair of stops 31, 32, the switch being then in the "off" position. Similarly, if the key be 25 turned contraclockwise, the pin 25 of the latch plate will be moved radially outward by the end *y* of the cam slot, and the latch 30 will be moved outwardly until its clears the 30 outer edge of the detaining lock 32, when the meantime tensioned spring 33 will throw the rotary switch piece to the next position, with the latch 30 between the next two adjacent stops 31, 32.

I claim as my invention—

35 1. A key socket for electric lamps, having an insulating body with line terminals and

lamp terminals and provided with a rotary key spindle, a switch piece rotatably mounted on said spindle, contacts co-operating with the switch piece, a transversely movable latch plate connected to and rotating with the switch piece, a switch operating spring, means to tension said spring on the rotation of the switch spindle, stops engaged by and serving to temporarily detain said latch 40 plate against rotation in either direction, and a cam moving with the switch spindle and operatively associated with said latch plate and stops to effect their disengagement upon rotation of the spindle in either direction, substantially as described. 45

2. In a switch for key sockets for electric lamps, a rotary key spindle, a switch piece rotatably mounted thereon, a latch plate engaging said switch piece to rotate therewith but transversely slidable thereon, stationary stops engaging said latch plate to temporarily detain the same against rotation in either direction, and a rotary cam moving with the key spindle and operatively 55 engaging said latch plate to shift it transversely out of engagement with said stops on the rotation of the spindle in either direction. 60

In testimony whereof I have signed my 65 name to this specification, in the presence of two subscribing witnesses.

ARTHUR W. CLAUDER.
